MECHANICAL TOY

Max Schmid, Nuremberg, Germany

Application March 3, 1936, Serial No. 66,890
In Germany November 19, 1935

11 Claims.

(Cl. 46—1)

This invention relates to a mechanical toy in the form of a pocket lens or the like and it is distinguished in that in the apparatus articles are moved in horizontal and vertical directions 5 and that by suitable means it is rendered impossible for the person who looks into the toy to see how the same operates.

An embodiment of the invention is illustrated by way of example in the accompanying drawing in which:—

Fig. 1 is a longitudinal section through the toy.

Fig. 2 is a top plan view of the toy.

Fig. 3 shows a top plan view of the apparatus 15 similar to a pocket lens.

Fig. 4 shows in side elevation how two flying machines are fixed on the glass pane.

In the toy shown in Figs. 1 and 2 a casing *a* like that of a pocket lens is closed at the front 20 and at the rear by open lids *b* and *c* respectively. The casing *a* has a downwardly directed extension *d* in which a spring motor *f* is mounted adapted to be wound up by a key. The spring motor can be temporarily stopped by means of 25 a spring controlled lever *g* which has an upwardly projecting rack *h* meshing with the pinion of the spring motor. When this rack *h* is in engagement with the pinion, the spring motor is stopped and it is released as soon as the rack is moved 30 out of engagement with the pinion. The spring motor *f* carries on the outer side a spur wheel *i* meshing with the holes of a perforated rim of a cylinder *k* mounted in the casing *a*. The cylinder *k* is rotated by the spur wheel *i*. On or 35 in the cylinder *k* a glass pane, mirror or other polished disc *l* is fixed so that it rotates with the cylinder. On the front side of this glass pane *l* a suitable toy, for instance a flying machine *m* is fixed by suitable means so that this flying 40 machine moves together with the glass pane and in horizontal or vertical direction according to whether the casing is in the horizontal or vertical position. The glass pane *l* is covered by an open ring *n*. Behind cylinder *k* a stationary cylinder *o* is mounted so that it is impossible to see from 45 the outer side that the cylinder *k* rotates. The cylinder *o* is secured in position by a ring *p*. Between the cylinder *o* and this ring *p* a transparent pane *q* is mounted, on which landscapes or other illustrations are painted. The casing *a* has apertures *r* in its circumference which are 50 covered by gelatine strips *s* through which the daylight falls into the interior of the casing so that the gyrating articles, such as the flying machine, can be clearly seen. To make it diffi-

cult or impossible for the viewer to recognize the manner in which the toy operates, a colored transparent disc *t* is mounted in the cover *b*, preferably a yellow transparent. This transparent disc *t*, through which the viewer looks into the pocket lenslike casing serves further to protect the glass pane against dirt or dust and to render the rotatable glass pane invisible so that the manner of operation of the rotating toy is rendered even more difficult. Only the rotating 10 flying machine which carries out a looping in the position shown in Fig. 1 and the background on the painted transparent *q* are visible.

In the form of construction shown in Fig. 3, the disc *u* forming the background has plastic 15 ornamentation and the spring motor is arranged under this disc *u*, the construction being otherwise similar to that shown in Figs. 1 and 2. In order to further improve the effect for the viewer several flying machines *m* are mounted on the 20 glass pane *l* and arranged the one above or at the side of the other. The flying machines may be directly fixed on the glass pane *l* or as shown in Fig. 4 by means of bows or the like. The daylight passes also through the toy shown in 25 Fig. 3. The interior of the toy may be lighted by electric means instead of by daylight.

The toy may be composed of two pocket lenslike casings in the form of a telescope, the spring motor being then mounted in the middle between 30 these casings. The rotating figure may be mounted on a rod near the edge of the casing, this rod being hidden by a ring so that it cannot be seen. In this instance the rotating glass pane is omitted. The driving of the glass cylinder with the flying machine may be electric or a periodically operated pressing or segment mechanism may be employed. Several glass panes may be arranged in the casing, which by suitable means are raised and lowered either 35 alone or together with the rotating cylinder, for instance by curves, eccentrics or the like.

I claim:—

1. A mechanical toy comprising in combination a cylindrical casing, a cylinder open at both 45 ends rotatable in said casing and having perforations near one end, a spur wheel engaging in said perforations, a spring motor carried by said casing and in driving connection with said spur wheel to rotate said cylinder, means for controlling said 50 motor projecting from said casing, a disc closing the rear end of said casing and provided with a picture forming a background, a transparent frame carried by and rotatable with said cylinder, and at least one toy article such as a flying ma- 55

- chine, fixed eccentrically on said frame, and adapted to move in a circular path in front of said rear disc during the rotation of said cylinder.
2. A mechanical toy as specified in claim 1, in which the rear disc is translucent.
3. A mechanical toy as specified in claim 1, in which the rear disc is opaque and is a plastic representation of a background.
4. A mechanical toy as specified in claim 1 in which the rear disc is opaque and the spring motor is accommodated behind said rear disc.
5. A mechanical toy as specified in claim 1 in which the casing has a lateral extension accommodating the spring motor.
- 15 6. A mechanical toy as specified in claim 1 in which a ring is fixed in a casing at the rear end of said rotary cylinder, said ring adapted to guide the rear end of said rotary cylinder and hide the rotating movement thereof.
- 20 7. A mechanical toy as specified in claim 1 in which a stationary cylinder is arranged in said rotary cylinder, secured on the casing at its front end by a ring adapted to guide said rotary cylinder and conceals the movement thereof.
8. A mechanical toy as specified in claim 1 in which the front end of said casing is closed by an open lid carrying a transparent disc.
9. A mechanical toy as specified in claim 1 in which the front end of said casing is closed by an open lid carrying a yellow transparent disc.
10. A mechanical toy as specified in claim 1 in which the casing has lateral apertures at its front end adapted to allow light to pass into the casing to illuminate the article on the transparent frame.
11. A mechanical toy as specified in claim 1 in which the means for stopping the spring motor comprise in combination a spring loaded lever 15 axially shiftable in and projecting from the casing, a rack projecting at right angles from said lever and a pinion driven by said motor and adapted to be brought into and out of mesh with said rack to stop and release said motor. 20

MAX SCHMID.
